UNITED STATES PATENT OFFICE.

JOSEPH L. HILLER, OF MATTAPoisETT, MASSACHUSETTS.

PULVERIZER.

1,135,795.

Specification of Letters Patent. Patented Apr. 13, 1915.

Application filed April 29, 1908. Serial No. 429,834.

To all whom it may concern:

Be it known that I, JOSEPH L. HILLER, a citizen of the United States, residing in Mattapoisett, Massachusetts, have invented 5 certain Improvements in Pulverizers, of which the following is a specification.

One object of my invention is to provide a machine which shall be capable of reducing to any desired degree of fineness granular or lump material, such as coal, and I further desire that the device forming the 10 subject of my present invention shall be of relatively simple and inexpensive construction, as well as of high capacity.

15 It is further desired to provide a pulverizer which shall include a casing of such construction that material thrown from a suitable rotating structure within it shall, if over a predetermined size, be returned to 20 such rotating structure, while if it is under this size it will be discharged from the machine.

Another object of the invention is to provide a pulverizing machine which shall 25 break or comminute the material fed to it by delivering this upon a rapidly turning disk or plate so that it is violently thrown off against suitable structures with great force, the fine crushed or broken material 30 being permitted to pass away from the machine, while all particles above a predetermined size are returned to the disk or plate to be again thrown off under the action of 35 centrifugal force and further broken or crushed.

It is also desired to provide a pulverizing machine having the above noted characteristics with means for governing the feed of material to the revolving plate or disk and 40 also means for facilitating the pulverizing of material under treatment as well as the separation of the fine particles from those which are coarser.

These objects I attain as hereinafter set 45 forth, reference being had to the accompanying drawings, in which:

Figure 1, is a vertical section of a machine constructed according to my invention; Fig. 2, is an inverted plan view of the 50 cover or guiding top of the machine. Fig. 3, is a plan of the machine with the cover removed; Fig. 4, is a vertical section of a modified form of my invention; Figs. 5 to 8, are vertical sections of various forms of 55 hopper and casing which may be used in carrying out my invention; Figs. 9 and 10,

are plans illustrating special forms of hopper; Fig. 11, is an elevation of a modified form of the revoluble disk, and Fig. 12, is a fragmentary vertical section showing a construction of parts which may be used when 60 balls are employed to assist in the pulverizing operation.

In Figs. 1 to 3 of the above drawings, A represents a suitably constructed base having a step bearing a for a vertical shaft B and also provided with an upwardly extending hollow portion open at one side, in the top part of which is a second bearing for the upper end of the shaft B, or, in the present instance, for the extension b thereof, 65 upon which is mounted the disk or plate b' . The shaft B has mounted upon it a pulley b^2 driven in any suitable manner; in the present instance by means of a belt b^3 . Mounted 70 upon the base A is a cylindrical body C open at the bottom and formed with an inwardly extending part a' of the base in such manner as to form therewith a chamber completely 75 closed off from the remainder of the interior of said body.

As above noted the extension b of the shaft B has fixed to it in any suitable manner a substantially horizontal plate or disk b' , 80 which is preferably provided upon its upper surface with a number of upwardly projecting spirally formed vanes or ribs b^4 , though these may be omitted in some instances if found advisable.

The portion a' of the base A and the body 85 C together serve to support a dished receptacle D, the center of whose bottom part is formed by the disk b' . In the bottom and sides of this receptacle are a number of 90 openings or holes d which constitute the screen or sieve portion of my machine, though, if desired, there may also be openings in the revoluble plate or disk b' as shown in Figs. 5 to 8 at d^5 . At suitable intervals I preferably mount within the part 95 D a number of directing valves d' , which also serve the function of abutments upon which the pieces of material thrown off from the plate b' may strike.

These vanes are usually spirally curved and extend from points adjacent to the opening for the disk b' to the upper edge of the receptacle. In some cases I employ 100 balls Q to aid in the pulverizing and under 105 these conditions curve or fillet the vanes d' so as to increase the available grinding sur-

face capable of being engaged by the balls.

Mounted upon the part D is a cover E usually having its central portion made in a generally funnel shaped form so as to provide a hopper for the reception of material, there being an opening e in the center of this cover so placed as to deliver material directly upon the central portion of the plate b'.

If desired, however, the opening may be 10 annular in form, as shown in Figs. 4 and 9, and may be in any suitable situation and of any desired form to properly deliver material to the disk b'.

The interior surface of the cover E is 15 also formed with a number of vanes e' and it will be noted that said surface is so curved and united with the inner surface of the receptacle D that it is practically continuous therewith; that is to say, the portions 20 of the receptacle D immediately adjacent to the outer edges of the plate b' are substantially continuous with the surface of said plate and from this latter the receptacle D is gradually curved upwardly until 25 its surface meets the surface of the cover E. This latter is so formed that while the top of its outer part forms a hopper for the reception of material, its inner surface is so curved as to be capable of directing material 30 so as to cause it to be delivered to the plate b' after it has been violently thrown off therefrom.

Under operating conditions coal or other material to be broken or pulverized is 35 delivered into the hopper formed by the cover E, and the shaft B and the plate b' attached thereto are turned at a high velocity, in the present instance by means of the belt b^s. The material fed and resting upon said 40 plate b' is thus turned at a high speed until it is thrown off under the action of centrifugal force so that it violently strikes the side portions or the vanes d' of the casing formed by the receptacle D and the cover 45 E, and is crushed or pulverized thereby.

As above noted, the pulverizing action may be facilitated and the capacity of the machine increased by the use of the balls which are of hardened metal and grind the 50 material under treatment in the manner similar to that ordinarily occurring in ball mills. As the material is crushed or pulverized it passes through the holes d in the interior of the body C from which it may fall into any suitable receptacle; it being noted that the part c of said body, as well as the upwardly extending part a' of the base structure, effectually serves to protect the belt and step bearing a from the broken 55 or powdered material. As shown in dotted lines in Fig. 1, the above mentioned parts are so sloped as to direct material passing through those of the holes d over the belt and pulley to opposite sides of the casing.

60 The pieces of material in the casing

formed by the receptacle D and the cover E which are still of too great a size to pass through the holes d, are directed upwardly by the curved surface of the receptacle D and strike the interior surface or vanes of 70 the cover E, where further crushing or pulverizing takes place while the unbroken pieces are directed back from said surface onto said plate b' from which they are again thrown off to be further broken. It is 75 noted that the curvature of the inside of this cover is such that the large or unbroken pieces of material are repeatedly guided back to the revolving plate, which is turned at such a velocity as to most efficiently perform the above noted operations; it being 80 obvious that the material acted upon is very thoroughly and rapidly pulverized to any desired fineness.

It will be further noted that there are but 85 few moving parts to the device and with the exception of the plate, these are thoroughly protected from injury from the material acted upon. Said plate itself may be easily removed and replaced since it is 90 preferably bolted to the flanged extension b of the driving shaft B so as to be quickly detached therefrom. The vanes b', d' and e' may be fixed in position either radially of 95 the shaft B or may be given any desired inclination relatively to planes radial of said shaft as may be found to most efficiently direct and assist in the pulverizing of the material acted upon.

In place of providing the vanes b' on the 100 plate b' I may if desired make said plate with a series of radial corrugations, as indicated at B', in Fig. 11. The walls of these corrugations, as is obvious, serve in effect 105 as ribs or projections whereby a high speed of revolution is imparted to any material resting upon said disk, with the result that this is thrown off and crushed or pulverized in the manner previously set forth.

In Fig. 2, I have shown a series of 110 removable guide vanes e' as mounted on the inner surface of the top or cover E. While these may be arranged in any desired manner so as to provide flat surfaces projecting in the paths taken by material flung off from the central revolving plate b', I preferably 115 mount them as shown in Fig. 2, in a number of series each of which defines a generally spiral line; it being obvious that similar vanes may be mounted on the receptacle D or main portion of the casing.

In that form of my invention illustrated in Fig. 4, I have employed a body completely closed at the sides as indicated at C'. Within this is mounted an electric motor G which is also completely inclosed and so arranged that its armature shaft B' is vertical, as in the case of that form of my device illustrated in Fig. 1. The upper end 125 of this shaft carries the plate b', and pul- 130

- verized material passing through the holes d of the container D may fall through the casing C' into any suitable bin or other receptacle. In this instance the cover E' forming the top of the pulverizing casing is provided with an annular hopper e^s so constructed that material passing through it is delivered over an annular area of the plate b' instead of directly in the center thereof.
- 5 10 The motor casing is preferably provided with a stuffing box g whereby entrance of grit or pulverized material along its armature shaft to its interior is effectually prevented.
- 15 In Fig. 9, I have illustrated in plan the construction of the hopper e^s employed in this form of my invention and in Fig. 10 I have shown an arrangement in which the material is delivered through a pair of 20 oppositely disposed spouts or chutes e^s formed in the cover E^s so as to discharge the material upon the revolving disk b' at two points 180° apart.
- In Figs. 5, 7 and 8, I have shown various 25 forms of adjustable hoppers whereby the feeding of material to the plate b' may be regulated. For example, in Fig. 5, I provide the center of the plate with a conical boss b^s placed centrally under the hopper e^s . This 30 hopper is provided with an interior sleeve e^s which has laterally projecting lugs e^s extending under the lower edge of the main part of the hopper. These lugs are engaged by bolts e^{10} whereby said sleeve may 35 be raised or lowered to vary the distance of its lower edge from the revoluble plate b' and thus to regulate the amount of material passing from the hopper into the casing of the machine.
- 40 In the case illustrated in Fig. 7, I have shown the adjustable hopper sleeve e^s as provided with lugs projecting from its top edge outside of the machine and in this case the bolts e^{11} pass through suitably formed 45 lugs on the hopper. As before, by means of these bolts the adjustable hopper sleeve may be moved toward or from the disk b' in order to regulate the feed of material to the machine.
- 50 In Fig. 8, I have shown a modification of the invention in which the adjustable hopper sleeve may be raised or lowered by means of hand levers f fulcrumed to the outside of the casing of the machine, which 55 levers may if desired be clamped in any adjusted position by means of wing nuts f' operative on their pivot bolts.
- In Fig. 6, I have shown in detail a construction employed where it is desired to 60 pulverize any material to what is practically an impalpable powder or to obtain such a powder as a by-product, as in the construction shown in Fig. 1. In this case I provide the upper portion of the cover with a hollow extension and perforate that portion of said
- cover which forms the bottom of this extension. These perforations d^s are of sufficient size to prevent the entrance of large particles of material into the extension of said casing, which may be flanged or otherwise provided with means for the attachment of a conduit H leading from it to any suitable exhausting device connected to the extension h . In the conduit H is an auxiliary screen h' of any desired degree of fineness whereby the size of particles of powdered material passing off from the conduit may be determined.
- 70 While in Fig. 6 I have shown perforations d in the body D and also perforations in the 80 revoluble disk d' , these two latter may be omitted if desired when it is wished to obtain merely the exceedingly fine particles which may be drawn through the extension h and the conduit H .
- 85 I claim:
1. The combination of a plate; means for supporting said plate in a substantially horizontal plane; means for rotating the plate; a stationary annular screen in the form of a 90 structure having its interior surface curved continuously with and surrounding said plate; vanes on said screen for directing and delivering the material thrown off from the plate; with a cover projecting downwardly 95 over the plate for returning thereto material thrown off the same.
  2. The combination of a casing having a portion of its interior formed by a movable plate; means for turning said plate relatively to the casing; said casing having its interior curved continuously with the plate and terminating in a portion directed downwardly toward and extended over the latter in position to return to the plate the material 105 thrown off therefrom; with means for permitting the escape of pulverized material; and spiral vanes projecting from the inner surface of the casing.
  3. The combination of a stationary casing having its top portion constructed to exteriorly form a hopper for the reception of material to be pulverized; with a device placed to receive material from said hopper and throw it forcibly against the walls of 110 the casing, the upper interior portion of said casing being formed by the exterior of the hopper and shaped to return to said device the material thrown off by it.
  4. The combination of a casing having a 120 central revoluble plate continuous with the adjacent portions of the casing, a cover having its interior surface continuous with the side portions of the casing and interiorly curved to return to the plate material thrown 125 off from it, with spirally curved vanes on the body of the casing and on the top thereof; and means for rotating the plate.
  5. The combination of a revoluble plate having vanes, means for driving said plate, 130

a casing inclosing said plate and constructed continuously with the plate to return thereto material thrown off from it, a screen for permitting escape of fine material, and vanes 5 on the screen and the inside of the casing.

6. The combination of a stationary casing having perforations; a perforated rotatable structure in said casing; and means for rotating said structure, the casing having 10 means to return to the rotatable structure the coarse particles of material thrown off therefrom.

7. The combination of a casing; a rota-

table structure therein, said casing being formed to return to said structure material 15 thrown off of the same; means for driving the structure; and vanes arranged in substantially spiral lines in said casing.

In testimony whereof, I have signed my name to this specification, in the presence 20 of two subscribing witnesses.

JOSEPH L. HILLER
